UNITED STATES PATENT OFFICE.

MERRITT A. HOLTON, OF FITCHBURG, MASSACHUSETTS.

LEATHER-SKIVING MACHINE.

SPECIFICATION forming part of Letters Patent No. 230,280, dated July 20, 1880.

Application filed June 12, 1880. (No model.)

To all whom it may concern:

Be it known that I, MERRITT A. HOLTON, of Fitchburg, State of Massachusetts, have invented certain new and useful Improvements 5 in Leather-Skiving Machines; and I hereby declare the following to be a full, clear, and exact description thereof, reference being had to the accompanying drawings, making part of this specification, in which—

10 Figure 1 is a front perspective view of the machine. Fig. 2 is a rear perspective view of the same. Fig. 3 is a longitudinal section through the upper feed-roll and its supports.

15 My invention relates to leather-skiving machines, and is an improvement on a machine patented by me October 8, 1879.

The object of my invention is to skive leather so as to leave it with a uniform thickness.

20 My invention consists, first, in an automatic feeding device which projects between the rolls at every revolution the under piece of a pile of regularly-cut pieces of leather, such as shoe counters, tips, &c.; secondly, in a swinging gage provided with an adjusting-screw and 25 offset to allow only a single piece of leather to be fed to the rolls at one time; and, thirdly, in an adjustable bearing for the upper feed-roll, whereby I prevent it from tipping or canting from wear or otherwise.

30 In order that those skilled in the art may make and use my invention, I will proceed to describe the manner in which I have carried it out.

In general construction as to feed-rolls, 35 knife, spring presser-arms, and supports the machine is substantially like that in Patent No. 220,286.

The automatic feed consists in a reciprocating bar, *a*, which moves in a slot in table A 40 by means of a crank, *b*, on the shaft of the lower feed-wheel, which carries a pitman, *B*, attached to a cross-head, *C*, fastened to bar *a* and moving in ways *d*.

The feed-plate *T* lies on the surface of the 45 table, and is fastened adjustably to reciprocating bar *a* by screws and holes *i i*, so that it reciprocates with said bar *a*, and as crank *b* turns said plate moves forward and catches a bit of leather and forces it between the rolls. 50 As bar *a* recedes the plate returns, and on the next stroke feeds forward another bit of leather.

The vertical guide-plate *D* is swung at its

upper edge by means of a hinge-pin, *e*, to a post, *E*, which rises from the frame. 55

Along the front edge of the guide-plate is a projecting rib, *f*, which does not extend quite to the lower edge of the plate, there being room for one of the pieces of leather to pass beneath it as the feed-bar pushes it forward. 60

Through post *E* passes a thumb-screw, *F*, the end of which bears against the guide-plate and adjusts it.

In order to provide against the upper roll tipping or sagging from wear or otherwise, I 65 provide the end, heretofore free, with a bearing constructed as follows: An arm, *G*, of the frame projects over the upper roll and in a line with its axis, and has on its end a downwardly-projecting forked bearing, *H*, the curvature of which is in a circle of somewhat larger diameter than the upper roll, so that said roll may be readily removed without disturbing the bearing. On the journal of the roll is a small hub, *i*, over which fits a ring, *I*, having the same 75 curvature as bearing *H*, and against which it fits snugly, so that the strain on the outer end of the roll is transferred to the ring *I*, and thence to bearing *H*.

A nut, *N*, secures the ring *I* onto the journal 80 of the upper roll.

Along the bed lies the curved spring *S*, which holds the pieces of leather against the guide-plate.

Having thus described my invention, what 85 I claim as new, and desire to secure by Letters Patent, is—

1. In a leather-skiving machine, the feeding device consisting of the reciprocating bar provided with the cross-head, as shown, pitman, 90 and crank on lower feed-roll, in combination with the slotted table A, substantially as described.

2. In a leather-skiving machine, the vertical swinging adjustable guide-plate *D*, provided 95 at its front edge with a rib, *f*, shorter than the guide-plate, for the purpose set forth.

3. In a leather-skiving machine, the projecting arm *G*, with its downwardly-projecting forked bearing *H*, in combination with the upper roll and the removable ring *I*, as and for 100 the purpose set forth.

MERRITT A. HOLTON.
